[57] CLAIM

The ornamental design of a christmas tree ornament, as
shown and described.

DESCRIPTION

FIG. 1 is a front view, with the top tilted slightly backward,
of my design, the design having ten points and being
approximately symmetrical about three vertical planes;

FIG. 2 is a side view of my design, with the ornament rotated
approximately 60° about its vertical axis from the position
shown in FIG. 1;

FIG. 3 is a top view of my design; and,
FIG. 4 is a bottom view of my design.
